WIRE ROPES

Robert Edward Campbell, Doncaster, England, assignor 5
to British Ropes Limited, Doncaster, England

Original application Sept. 10, 1954, Ser. No. 455,300.
Divided and this application Apr. 21, 1958, Ser. No. 729,673

Claims priority, application Great Britain Nov. 18, 1953

6 Claims. (Cl. 57—148)

This invention relates to steel wire ropes, strands, steel cores and/or finished or partly finished rope, irrespective of the type of core used or whether the ropes are stranded or locked coil, and is a divisional application of application Serial No. 455,300, filed September 10, 1954.

The invention is more especially, but not solely, applicable to steel wires which have been isothermally quenched (bringing them into the condition known as "patented") and then cold drawn. It is also applicable to constructions in which, say, filler wires which have not been isothermally quenched, are incorporated into a rope or core, the other wires of which have been isothermally quenched.

The invention consists of a multi-layered, steel-wire rope or core characterized in that the king wire is faceted according to the number of wires in the first layer over it and the wires of the intermediate layer or of each successive intermediate layer are individually of polygonal section, the section of the wires of the outer layer being that of a keystone with an arcuate head, this arc being a segment of the rope's or core's curved outer circumference and adjacent wire sections being in close contact with one another over their straight edges, whereby the wires are prevented from rolling in relation to each other. These steel wire ropes or cores are preferably made by imparting thereto a controlled degree of plastic flow with a uniform pressure all around as described and claimed in application Serial No. 455,300, of which this application is a division.

The invention will be further described with reference to the accompanying drawings.

Fig. 1 is a cross-section of a 9/9/1 rope according to the invention with a corresponding round wire rope indicated in phantom;

Fig. 2 is a cross-section of a 12/6/1 rope; and

Fig. 3 is a view similar to Fig. 1 of a 12/6/1 rope with filler wires.

In manufacturing wire ropes according to this invention, the preferred method utilizes the application of the combined resultant reactive force arising from plastic flow under compression, coupled with predetermined elongation of the strand, while passing the rope through a suitable die capable of providing a drawing action thereon.

Back tension is applied to the longitudinal axis of the strand as it passes into the die, of sufficient magnitude to initiate plastic flow prior to the strand entering the die, while not exceeding the limit of proportionality of the strand (that is, the point on a stress-strain curve at which the strain ceases to be proportional to the stress).

After this treatment, the originally round wires making up the rope will have been individually reformed to a geometric pattern in which the king wire has become faceted according to the number of wires laid over it, the point of contact of the next layer of overlying wires forming the base of a pentagon on each facet of the king wire, the next layer being of reversed pentagons and so on.

2

In Fig. 1, the king wire 1 is faceted with a plurality of sides 2 according to the number of wires 3 laid over it. The contact surface of the layer of wires 3 overlying the king wire forms, in cross-section the base of a pentagon on each side or facet 2 of the king wire, and the next layer of wires 4 forms reversed pentagons, and so on, producing an interpenetrating relationship between successive layers. A steel rope or core embodying this invention is materially smaller in external diameter than is a similar stranded rope or core formed of conventional round wire, indicated at 5, Fig. 1, where both contain the same total cross-section of metal. This results in a very considerable increase in the tensile strength of a rope of any given size, due to the increased cross-section of steel, which is proportional to the diminution of the air space within the rope, the small percentage of non-metallic material in the improved rope being occupied by internal lubricant. It has also been found that a rope or core made according to this invention has a markedly superior resistance to kinking, thus making its handling by unskilled labor much easier.

In the steel rope or core illustrated in Fig. 1, the two successive layers around the king wire are both formed of the same number of individual wires. In such a construction the outer layer of wires necessarily must have a cross-sectional area considerably larger than the next successive inner layer or the outer layer will result in a relatively thin flat-sectioned wire.

In some instances it may be found desirable and more practical to form the rope or core of individual wires having substantially the same cross-sectional area. Such a substantially uniform-sectioned multi-layered rope may have several combinations of shapes depending to a certain extent upon the number of wires in each layer and upon the utilization of substantially all of the cross-sectional area of the rope by the wires of uniform cross-section or by filling in some of the space in the rope by so-called filler wires.

The first type of construction is illustrated in cross-section in Fig. 2. As can readily be seen, in this arrangement six wires 6 are arranged around a hexagonal king wire 7, and twelve wires 8 are arranged in the layer surrounding the six-wire layer. In this construction the layer of wires 6 immediately adjacent to the king wire 7 are formed with pentagonal cross-sections, and the outer layer of wires 8, which contacts the outer periphery of the pentagonal wire layer, have a substantially quadrangular cross-section. In this construction, as in the arrangement illustrated in Fig. 1, the outer layer of wires is formed with the outer side 9 thereof as a segment of the circumference of the rope formed on a radius corresponding to the radius of the stranded rope. This results in a cross-section of the wires in the outer layer of a keystone configuration with an arcuate head, the arc of the head being that of the curved outer circumference of the rope. As can readily be seen, substantially all of the cross-sectional area of the rope is occupied by metal of the various wires forming the rope, so that all of the advantages obtainable by a construction such as that shown in Fig. 1 also inherently are obtained in this construction. In both of these arrangements an appreciable increase in the fatigue resistance of the rope or core is obtained. Various factors contribute to this greatly increased resistance to fatigue. Prominent among these factors, is the geometric shape of the wires forming the rope including the flat multi-sided configurations which prevent rolling of the wires on each other, as well as preventing relative rolling between layers of wires constituting the rope by the interpenetrating relationship of the successive layers. The plastically flowed surface film on the working or contact area of each wire also gives added fatigue resistance.

In addition, it has been found that rope made in accordance with this invention is not subject to premature failure of individual wires until the full expectation of fatigue life is obtained. At this latter stage, progressive failure of individual wires ensues in the normal manner with the outer wires failing by square-ended fatigue and the inner wires failing under pure tension. This has an added advantage in that, when it does occur, the failure takes place externally and not internally of the rope, thus giving adequate warning of the inability of the rope to sustain a given load. This advantage also results from the increased bearing surface of the wires and the inability of the wires to roll upon each other and of the rope to become distorted. This latter is generally the product of the geometrical wedge configuration of the wires forming the rope, especially in a construction shown in Fig. 2, which give the rope high resistance to compression and distortion, thus insuring that differential working of the individual wires is minimized with consequent elimination of premature fatigue in individual wires.

In certain instances it may be found desirable to include filler wires more completely to eliminate air space between wires forming successive layers around the king wire of a rope, and thereby more effectively to utilize all of the cross-sectional area of the rope for load-carrying metal elements. Such a construction is illustrated in cross-section in Fig. 3. The filler wires in such a construction normally have a substantially quadrangular diamond-shaped cross-section and are usually arranged between the outer adjacent edges of the flat sides of adjacent wires in one layer and the inner edges of the wires in the successive layer.

In Fig. 3 the wire rope includes a hexagonal king wire 10 surrounded by six wires 11 of substantially the same cross-sectional area as the king wire 10, with an outer layer of wires 12 arranged around the intermediate layer of wires 11. This rope has substantially the same configuration as that shown in Fig. 2 and, in addition, is provided with relatively small quadrangular diamond-shaped filler wires 13 in the space between the outer edges of adjacent wires 11 in the intermediate layer of wires and the adjacent surfaces of the outer layer of wires 12. As can be seen, these filler wires 13 also have substantially flat sides and result in two additional sides 14 on each of the intermediate layer wires 11 and one additional flat side 15 on each wire 12 in the outer layer of wires. Obviously, other arrangements of filler wires can be utilized between any of the wires and between any layers of wires. In this construction the wire rope is especially free of air gaps. The outer periphery 16 of the outer wires 12 also is formed as a segment of a circle corresponding to the outer circumference of the rope, as in the other constructions illustrated in Figs. 1 and 2.

In all of the ropes made in accordance with this invention, the even bedding of the strands to the core produces a tighter spun and less lively rope which results in improved flexibility, and the strands themselves have been found to exhibit substantially micro-interstices of uniform consistency. In addition, the substantial elimination of air spaces within the rope and the presence of internal lubricant on adjacent surfaces of the flat sides of the wires forming the rope, provide for maximum anticorrosion properties. This is particularly true since such stranded rope is highly water repellent and affords a minimum capacity for the retention of water between the wires comprising the rope.

While particular embodiments of this invention have been illustrated and described, modifications thereof will occur to those skilled in the art. It is to be understood, therefore, that this invention is not to be limited to the particular arrangements disclosed, and it is intended in the appended claims to cover all modifications within the spirit and scope of this invention.

I claim:

1. A multi-layered steel wire rope comprising a central

king wire and having at least one intermediate layer of wires and an outer layer of wires arranged around the king wire, said king wire being of polygonal cross-section and faceted corresponding to the number of wires in the first layer of wires surrounding it, the wires in the intermediate layers being individually of flat faced polygonal cross-section, and the cross-section of the wires of the outer layer being that of a keystone with an arcuate head, the arc of said head being that of the curved outer circumference of said rope, the wires in the first layer of wires surrounding said king wire each having one face engaging flush against a respective face of said king wire, the wires in each layer of wires having side faces engaging flush against the side faces of the wires adjacent thereto in the respective layer, the outer surfaces of the wires of each intermediate layer of wires having alternating flat faces disposed at an inclination to one another with each wire in the respective layer defining at least one of said faces, the inner surfaces of the wires of the next outward layer having complementary flat faces engaging flush against the said faces of the next inward layer, the faces of the individual wires in the rope being firmly engaged flush against the complementary flat faces of adjacent wires and, whereby successive layers of wire are disposed in interpenetrating relationship and the wires and the layers of wire are retained against rolling relative to each other.

2. A multi-layered steel wire rope comprising a central king wire, at least one intermediate layer of wires surrounding the king wire, and an outer layer of wires arranged around the intermediate layer, the king wire being of polygonal cross-section and faceted corresponding to the number of wires in the intermediate layer, each wire in the intermediate layer being of pentagonal cross-section pointing radially outwardly, the cross-section of each wire in the outer layer being quadrangular in shape with the radially outer side being curved to form a segment of the curved outer circumference of said rope, each wire at the faces thereof engaging flush against the respective faces of adjacent wires whereby the king wire and the intermediate layer of wires and the said intermediate and outer layers of wire are in interpenetrating relationship and thereby prevented from rolling in relation to each other.

3. A multi-layered steel wire rope comprising a central king wire, at least one intermediate layer of wires surrounding the king wire, an outer layer of wires arranged around the intermediate layer and filler wires between successive layers, the king wire being of polygonal cross-section and faceted corresponding to the number of wires in the first layer of wires surrounding it, the wires of the intermediate layers being in cross-section individual interfitting flat-faced polygons, the filler wires being diamond-shaped in cross-section, and the wires of the outer layer having flat side faces and flat inner faces in contact with adjacent wires and each having a curved outer surface forming a segment of the curved outer circumference of the rope, the outer faces of the wires of each intermediate layer of wires comprising alternating flat faces disposed at an inclination to one another with each wire in the respective layer defining at least one of said faces, the inner faces of the wires of the next outward layer comprising complementary flat faces engaging flush against faces of the next inward layer, the faces of the individual wires in the rope firmly engaging flush against the complementary flat faces of adjacent wires, whereby the successive layers of wires are disposed in interpenetrating relationship and the wires and the layers of wires are retained against rolling relative to each other.

4. A multi-layered steel wire rope, wires of individual layers having flat side faces and engaging with the flat side faces of adjacent wires of the same layer, the outer surfaces of the wires of each intermediate layer of wires having alternating flat faces disposed at an inclination to one another with each wire in the respective layer defining at least one of said faces, the inner surfaces of the

wires of the next outward layer having complementary flat faces engaging with the said faces of the next inward layer, the faces of the individual wires of the rope being firmly engaged flush against complementary flat faces of adjacent wires, whereby the successive layers are in close interpenetrating relationship and the wires and the layers of wire are retained against rolling relative to each other.

5. A multi-layered steel wire rope comprising a central king wire and having at least one intermediate layer of wires and an outer layer of wires arranged around the king wire, said king wire being of polygonal cross-section and faceted corresponding to the number of wires in the first layer of wires surrounding it, the wires in the intermediate layers being individually of polygonal cross-section, the cross-section of the wires of the outer layer being that of a keystone with an arcuate head, the arc of each head being that of the curved outer circumference of said rope, each of the wires in each layer being of the same cross-section, the wires in the first layer of wires surrounding said king wire each having one face coextensive with and engaging flush against a respective face of said king wire, the wires in each layer of wires having side faces extending radially of the axis of said king wire and coextensive with and engaging flush against

the side faces of the wires adjacent thereto in the respective layer, the outer surface of each wire of each intermediate layer of wires having at least two faces disposed at an inclination to one another and the inner surfaces of the wires of the next outward layer having complementary faces coextensive with and engaging flush against the said faces of the next inward layer, whereby the individual wires are firmly engaged flush against adjacent wires on all faces other than said radiussed heads, the successive layers of wire are disposed in interpenetrating relationship and the rope is substantially solid metal in cross-section.

6. A multi-layered steel wire rope as set forth in claim 1, wherein the wires in the layers of wire are individually of pentagonal cross-section and the wires in successive layers of wires alternately point in opposite directions radially in relation to the axis of the rope whereby the successive layers are in interpenetrating relationship.
